(57) **CLAIM**

The ornamental design for a tape measure guide, as shown and described.

DESCRIPTION

FIG. 1 is an upper, front, left side perspective view of a tape measure guide showing my new design, the broken lines show a tape measure and are for illustrative purposes only;

FIG. 2 is a top plan view thereof;

FIG. 3 is a bottom plan view thereof;

FIG. 4 is a left side elevational view thereof; the right side elevation being a mirror image thereof;

FIG. 5 is a front elevational view thereof;

FIG. 6 is a rear elevational view thereof; and,

FIG. 7 is an upper, front, left side perspective view thereof, showing the tape measure guide in an open position thereof, the broken lines show a tape measure and are for illustrative purposes only.
